UNITED STATES PATENT OFFICE.

ALFRED LAW MOWAT, OF SCHOLES, CLECKHEATON, AND ERNEST INGHAM, OF THE GRANGE, CLECKHEATON, ENGLAND.

METALLIC CLOTHING FOR OPENING, BREAKING, PREPARING, OR CARDING FIBROUS SUBSTANCES.

Application filed November 1, 1928, Serial No. 316,603, and in Great Britain September 19, 1927.

This invention relates to metallic clothing for opening, breaking, preparing or carding fibrous substances. Heretofore this form of clothing has usually been made in the form 5 of wire of a suitable cross section, with pieces cut out at proper intervals along it to leave a single row of teeth of the required shape for the production of the desired effect. The wire so formed is then wound around grooved 10 or plain surfaces of the cylinders or rollers to which it is to be applied to form multiple rows of teeth, its ends being secured by soldering, or in any other appropriate manner. The present invention has for its chief object to 15 introduce an improved form of metallic card clothing which will be quite as efficient as the kind described, be as cheap, or cheaper to produce, be capable of being applied without the use of skilled labor and be equally applicable 20 for covering curved or flat surfaces.

According to this invention instead of the metallic clothing being constructed from wire with a single row of teeth, it is constructed from metallic strip or sheet of iron, steel or 25 any other metal whatsoever, and numerous rows of teeth are obtained across the width of the ribbon or sheet by punching or stamping them out of the body of the material and bending them at right angles thereto, or to 30 any other desired angle.

The teeth may be punched out or stamped in any desired order or form and may follow any of the known methods of setting as employed in connection with wire card clothing. 35 To obtain closer setting, that is, more points per square inch, than can be obtained by punching, the body or foundation is corrugated or folded between the rows of teeth. The latter may be of any required form and 40 may vary from the comparatively long and slender teeth used in metallic clothing for carding, to the sawtoothed form of various degrees of coarseness, or even to the flat toothed form as used for removing burrs or 45 other foreign matter from certain fibres, or may be straight or curved or tapered from the base to point in either direction. The metallic strip or sheet may be of such character that it will enable the points or any other 50 part of the teeth to be hardened, or tempered

or ground either on the surface or down the sides, and it can be constructed of any desired thickness and composition to suit different classes of work. When the metallic clothing is made in sheet or fillet or ring form, the 55 ends, or sides, or both may be perforated at intervals or soldered or fitted with a prong, or be otherwise formed for attachment to the cylinders or rollers. The metallic clothing may be applied to any rollers or 60 cylinders or flats or any other mechanism used in the opening, breaking, preparing, carding of textile fibres to which it is applicable and any such roller or cylinder or flat or other mechanism may work in conjunction with an- 65 other roller or cylinder similarly covered with a different type of card clothing, or with a card clothing having a different formation of tooth or with metallic wire. When the metallic clothing is made for application to 70 flats it may be formed with marginal edges, adapted to be secured to the flats by bending and clamping or it may be formed with prongs to fit holes in the flats. If desired the bending operation may be effected before the 75 metallic clothing is pressed on to the flat and be done in such manner that a slight amount of lateral tension will be imparted to the foundation as it is pressed into contact with the flat for keeping it flat against the surface 80 of the latter when the marginal edges of the clothing are turned underneath the bottom edges of the flats. Flats so covered may work in conjunction with a cylinder covered with a similar type of metallic clothing, or with 85 clothing of any other appropriate form.

In the accompanying drawings, Fig. 1 is an elevation, Fig. 2 a plan, and Fig. 3 an end view of a form of metallic card clothing constructed in accordance with this invention. 90

A indicates the teeth, and B the metallic strip.

Referring to the example shown, the teeth A are punched out in rows arranged parallel with the edge of the strip B. This method of setting the teeth leaves comparatively wide spaces between the teeth. To reduce the width of these spaces the strip is folded or corrugated between the rows of teeth as shown at b. 95

What we claim as our invention and desire to secure by Letters Patent in the United States is:—

5 Clothing for opening, breaking, preparing or carding fibrous substances comprising a metallic sheet having teeth punched therefrom at an angle thereto and arranged close-

ly together in rows, the sheet being folded between the rows to bring the rows of teeth closer together.

In testimony hereof we have hereunto affixed our signatures.

ALFRED LAW MOWAT.
ERNEST INGHAM.
